J. LYALL.

CARPET.

No. 16,361.

Patented Nov. 3, 1885.

A B A B A B

UNITED STATES PATENT OFFICE.

JAMES LYALL, OF NEW YORK, N. Y.

DESIGN FOR A CARPET.

SPECIFICATION forming part of Design No. 16,361, dated November 3, 1885.

Application filed June 25, 1885. Serial No. 169,773. Term of patent 7 years.

To all whom it may concern:

Be it known that I, JAMES LYALL, of the city and State of New York, have invented and produced a new and original Design for Carpets, of which the following is a specification.

This design for a carpet is shown in the annexed photograph.

This design consists of the combination of stripes and checks, as shown. The checks A and B alternate in one range, the dark lines upon the checks A running diagonally in one direction, and the lighter lines on the checks B running diagonally in the other direction. Between the rows of checks A B is a second row of checks, C D, of nearly uniform width with the row of checks A B, and, in addition to the diagonal lines of the checks, there are

wide longitudinal stripes running through the center of the checks C D and narrow longitudinal stripes parallel therewith running between the respective rows of checks, as shown.

I claim—

The design for a carpet, consisting of the checks A B C D, there being stripes running through the center of the rows of checks C D and narrower stripes parallel therewith and between the respective rows of checks, as represented.

Signed by me this 19th day of June, A. D. 1885.

JAMES LYALL.
